US00D792867S

(12) **United States Design Patent** (10) **Patent No.:** **US D792,867 S**
(45) **Date of Patent:** **** Jul. 25, 2017**

(54) **HANDSET AND CRADLE UNIT ASSEMBLY
FOR A VIDEO PHONE SET**

(71) Applicant: **SORENSEN IP HOLDINGS LLC**,
Salt Lake City, UT (US)

(72) Inventors: **Conrad Arlo Maxwell**, Herriman, UT (US); **Eric V. Winsor**, West Jordan, UT (US); **Mark D. Nelson**, West Jordan, UT (US); **Merle L. Walker**, Sandy, UT (US); **Brent Carlen Giles**, Salt Lake City, UT (US); **Elie Mathias Monge**, San Francisco, CA (US); **Sean Patrick Murphy**, San Francisco, CA (US); **Shannon Colleen Fong**, San Francisco, CA (US); **Alice Viola Pintus**, Milan (IT); **Thomas Mitchell Dair**, Lafayette, CA (US)

(73) Assignee: **SORENSEN IP HOLDINGS LLC**,
Salt Lake City, UT (US)

(**) Term: **15 Years**

(21) Appl. No.: **29/593,705**

(22) Filed: **Feb. 10, 2017**

Related U.S. Application Data

(62) Division of application No. 29/565,050, filed on May 17, 2016, which is a division of application No. 29/518,646, filed on Feb. 25, 2015, now Pat. No. Des. 758,984.

(57) **CLAIM**

The ornamental design for a handset and cradle unit assembly for a video phone set, substantially as shown and described.

DESCRIPTION

FIG. 1 is a perspective view of a handset and cradle unit assembly for a video phone set showing our new design.

FIG. 2 is a front view of the handset and cradle unit assembly for a video phone set of FIG. 1;

FIG. 3 is a back view of the handset and cradle unit assembly for a video phone set of FIG. 1;

FIG. 4 is a right side view of the handset and cradle unit assembly for a video phone set of FIG. 1;

FIG. 5 is a left side view of the handset and cradle unit assembly for a video phone set of FIG. 1;

FIG. 6 is a top view of the handset and cradle unit assembly for a video phone set of FIG. 1;

FIG. 7 is a bottom view of the handset and cradle unit assembly for a video phone set of FIG. 1;

FIG. 8 is a perspective view of the handset of the video phone set of FIG. 1, shown separated from the cradle unit for clarity of disclosure;

FIG. 9 is a front view of the handset of the video phone set of FIG. 1, shown separated from the cradle unit for clarity of disclosure;

FIG. 10 is a back view of the handset of the video phone set of FIG. 1, shown separated from the cradle unit for clarity of disclosure;

FIG. 11 is a right side view of the handset of the video phone set of FIG. 1, shown separated from the cradle unit for clarity of disclosure;

FIG. 12 is a left side view of the handset of the video phone set of FIG. 1, shown separated from the cradle unit for clarity of disclosure;

FIG. 13 is a top view of the handset of the video phone set of FIG. 1, shown separated from the cradle unit for clarity of disclosure;

FIG. 14 is a bottom view of the handset of the video phone set of FIG. 1, shown separated from the cradle unit for clarity of disclosure;

FIG. 15 is a perspective view of the cradle unit of the video phone set of FIG. 1, shown separated from the handset for clarity of disclosure;

FIG. 16 is a front view of the cradle unit of the video phone set of FIG. 1, shown separated from the handset for clarity of disclosure;

FIG. 17 is a back view of the cradle unit of the video phone set of FIG. 1, shown separated from the handset for clarity of disclosure;

FIG. 18 is a right side view of the cradle unit of the video phone set of FIG. 1, shown separated from the handset for clarity of disclosure;

FIG. 19 is a left side view of the cradle unit of the video phone set of FIG. 1, shown separated from the handset for clarity of disclosure;

FIG. 20 is a top view of the cradle unit of the video phone set of FIG. 1, shown separated from the handset for clarity of disclosure; and,

FIG. 21 is a bottom view of the cradle unit of the video phone set of FIG. 1, shown separated from the handset for clarity of disclosure.

The broken lines consisting of a long dash and two short dashes seen on the figures showing the logos on the top and bottom of the handset, the microphone and speaker holes of the handset, and the cord and connector on the front of the handset, the cord on the cradle unit, mounting structures on the inner portion of the cradle unit, and the feet on the bottom of the cradle unit represent environmental structure and form no part of the claim.
